UNITED STATES PATENT OFFICE.

JOHN HENRY THOMAS, OF MEDINDIE, SOUTH AUSTRALIA, AUSTRALIA.

BOGIE FOR RAILWAY AND TRAMWAY VEHICLES.

1,307,326.

Specification of Letters Patent. Patented June 17, 1919.

Application filed October 21, 1918. Serial No. 258,982.

To all whom it may concern:

Be it known that I, JOHN HENRY THOMAS, a subject of the King of Great Britain and Ireland, residing at No. 30 Hawkers road, 5 Medindie, State of South Australia, Commonwealth of Australia, have invented certain new and useful Improvements in Bogies for Railway and Tramway Vehicles, of which the following is a specification.

10 It is well known that with these bogies as heretofore constructed and connected to the body main frame whether of a tramcar, railway carriage or truck or of a locomotive, that is with a king pin at the center or near 15 the center of a rigid or one piece bogie frame, there is excessive wear of the rails and of the wheel flanges when the bogie is passing around any curve. This is due to the fact that the two axles are maintained at 20 all times in position parallel one to the other and cannot take positions truly radial to the curve, and consequently the wheel flanges cannot take positions truly tangential to the rails, but tend to ride upon the rails 25 to their mutual destruction.

According to my invention the frame of the bogie is made in two parts each carrying one of the axles, such parts being held together by a vertical king pin but being capable of some relative movement one to the other about the king pin, and being held to the body of the tramcar or vehicle by means of a link with two oppositely projecting pins operating in combination with a somewhat 35 V shaped beam with two downwardly projecting pins. One of the pins projects downward from the link and passes through eyes in the two parts of the bogie and serves as the said king pin and the other pin projects 40 upward and passes through a hole in the center of the somewhat V shaped beam into a hole in the center of a beam rigidly secured to the frame of the vehicle body. The two pins on the somewhat V shaped beam 45 project downwardly therefrom one at each end and engage slidable blocks slidable upon inclined horn plates secured upon the opposing faces of the two parts of the bogie frame and governing the before mentioned 50 relative movement of the same.

The sidewise movement of the bogie relatively to the vehicle frame as the bogie enters a curve carries it over relatively to the frame of the vehicle body and therefore relatively to the somewhat V shaped beam, the two depending governor pins and the slid-

able blocks so that when passing around a curve of any radius the two parts of the bogie are moved automatically into such position that the two axles take up positions 60 truly radial to the rails and consequently the wheel flanges take up positions truly tangential thereto.

The weight of the tramcar or vehicle is supported by the bogie by means of bearing 65 blocks fastened to the underside of the car body frame and slidable upon bed plates upon the bogie, the frame of the bogie being supported by springs suspended between the frame of the bogie and the axle boxes. 70

In order that my invention may be clearly understood I will describe the same with reference to the accompanying drawings in which only the essential features are shown, details of the design and fastening together 75 of the several parts being left to be filled in according to the make of car or vehicle to which the invention is to be applied.

Figure 1 is a plan view partly in section, showing a bogie constructed according to 80 my invention as running upon a length of straight track, and Fig. 2 is a similar view, but with no section, showing the bogie as running upon a length of curved track. The sectional portion of Fig. 1 shows the top 85 flanges of one of the H beams removed to more clearly show the inclined horn plates 14. In these two figures I have shown and shaded with vertical lines the bearing blocks 28 secured to the frame of the car body. I 90 have also indicated by dotted lines the position of the side beams of the vehicle body frame and by an arrow the direction of movement of the vehicle.

Fig. 3 is a side view, partly in section, 95 showing the bogie as in Fig. 1 together with portion of the frame of the car body but with the near side channel iron of that frame removed, and showing the bearing blocks 28 in section; the sectional part being upon the 100 line a b of Fig. 1 to show more clearly the king pin 5 and connections for operating the slidable governor blocks 10.

Fig. 4 is a sectional view upon line c d of Fig. 1 to show more clearly the slidable governor blocks 10 and the horn plates 14 between which they operate. 105

Fig. 5 is an end view from the front showing in particular the means for supporting the car body frame upon the bogie. 110

Fig. 6 is also an end view from the front showing in particular the means for connect-

ing the car body frame to the bogie, and the side springs, but the front half of the bogie is removed to show said connection more closely.

- 5 According to my invention the frame of the bogie is made in two parts, front and rear, each part having at one end an axle with a pair of wheels, and at the other end an eye, the eyes of the two parts being
 10 marked 3 and 4 respectively, in which eyes is fitted a king pin 5 whereby the two parts are held together and about which they may make a relative swinging movement in a horizontal plane. The eyes 3 and 4 are formed
 15 preferably by steel castings fitting one another concentrically and bolted or riveted to the H beams of the bogie frame.

At each side of the king pin 5 are formed two opposing inclined faces, that is to say
 20 the rear face 8 of the forward part of the bogie and the forward face 9 of the rear part of the bogie at each side of the king pin are specially shaped or inclined in a horizontal plane being widest apart at the
 25 end next to the king pin and closer together at the outer end, and between them they carry slidable blocks 10 arranged in pairs, each pair of blocks forming between them a socket for one of the governor pins 12 which
 30 project from the somewhat V shaped beam 11 and being so proportioned and inclined that when the bogie is running upon a straight length of track the governor pins 12 with the blocks 10 are at about the center
 35 of the inclined faces 8 and 9. The slidable blocks 10 must be made in parts or pairs so that they may adjust themselves upon the governor pins 12 as they cause the angle between the opposing faces 8 and 9 to vary.
 40 This it does however to a very slight extent only.

Preferably the frame of each half of the bogie is constructed of two flanged end plates 1, 1 of cast steel connected together by four
 45 beams 2, 2 of H or of channel section, two below and two above, and the before-mentioned opposing faces are formed by means of blocks 14 either of cast or wrought metal forming as it were horn plates which are securely fastened to the lower of such beams as indicated more particularly in Figs. 1 and 4.

The link 16 with two oppositely projecting pins is positioned so that the pin 5 upon
 55 its one end projects downward and serves as the king pin to hold together the two parts of the bogie while the pin 17 upon its front end projects upward and serves as a coupling pin which passes through the somewhat V shaped beam 11 and into a hole in a beam 19 secured to the main frame 18 of the vehicle body and so couples the bogie to the main frame, and in the case of a tramcar driven by motors on the bogie carries the
 60 body forward with the bogie or in the case
 65

of a railway carriage carries the bogie forward with the body.

The somewhat V shaped beam 11 lies between one of the H beams 2 of the bogie and the beam 19 secured to the main frame 18 of the vehicle and has at its center an eye or hole which fits upon the upwardly projecting pin 17 of the link 16 and at each end a downwardly projecting governor pin 12 which pins 12 pass through the before mentioned slidable governor blocks 10 and each of which has a collar and pin below the slidable block.

The amount of incline upon the faces 8 and 9 of the horn plates 14 in a tramcar or railway vehicle other than a locomotive depends upon the distance the rear corner of the rear part of the bogie is behind the upwardly projecting pin 17 of the link 16, that is behind the point of attachment of the bogie to the main frame.

In the case of an electric tramcar in which one or both of the axles is fitted with an electric motor, should more strength be required to assist the king pin 5 to cause the 90 motors on the bogie to push the car, a light turntable may be placed on the pivot point 30 of the rear half of the bogie with concentric rings or other suitable connection.

To assist in returning the two parts of the 95 bogie to central or normal position after displacement in rounding a curve and to assist in maintaining them in central position when running on the straight I provide upon each side a strong spring 20 carried by 100 and projecting from a bracket 21 secured to the side beam of the frame 18 of the vehicle body and adapted to engage by means of a flanged head the slidable blocks 10 of the bogie. These springs 20 are so controlled 105 by a central bolt 23 that when the blocks 10 are in their central or normal position their heads just touch but do not exert any further pressure upon the blocks. When rounding a curve the spring upon the outside of the curve is compressed by the outward movement of the corresponding slidable block but the spring upon the inside cannot follow its block. The result is that the full power of the outside spring is available to assist in returning the outside block 110 to normal position.

The weight of the vehicle is supported by the bogie by means of flanged bed plates 25 secured to the top of the bogie frame and by 120 bearing blocks 28 secured to the underside of the frame of the car body. The bearing blocks 28 have curved outer ends, and the flanges 26 of the bed plates 25 are curved also but to a slightly greater radius. Between the curved outer ends of the blocks 28 and the flanges 26 of the plates upon the rear part of the bogie provision is made for a slight freedom or sidewise movement, but between the ends of the blocks 28 and the 125 130

flanges 26 of the plates upon the front part of the bogie provision is made for considerable movement, sufficient to permit the bogie to move over sidewise when rounding the 5 sharpest curve on the track before the block contacts with the flange.

The bogies are always placed beneath the vehicle body with the beam 11 toward the end of the car so that when the bogie is at 10 the front of the car the beam is toward the front and when at the rear it is toward the rear, and the several parts operate correctly when passing around a curve whether the bogie is at the leading or the trailing end of 15 the car, so that the reversing of the direction of the car makes no difference to its operation.

I will now describe the movement of a bogie constructed and attached as above described.

When running upon a straight road the governor pins 12 are maintained in position at an equal distance from the center of the bogie, and the two axles are parallel to 25 one another as shown more particularly in Fig. 1.

When the vehicle enters a curve however the front wheels and axle of the bogie move over with the curve while the front of the 30 body frame of the vehicle carrying with it the governor pins 12 is held by the blocks 28 and the flanges 26 of the beds 25 over toward the outside of the curve. So soon as 35 this movement commences the block 28 of the main frame comes against the flange 26 of the rear bed plate 25 of the bogie which then acts as a fulcrum, and the connection to the main frame through the upwardly projecting pin 17 of the link 16 carries the 40 V shaped beam 11 and consequently the two governor pins 12 toward the outer side of the curve. This sidewise movement of the pins 12 through the blocks 10 operates upon the opposing inclined faces 8 and 9 of the 45 frame of the bogie and causes the two parts of such frame to swing somewhat about the king pin 5, the inclined faces of the horn plates upon the outer side of the curve being forced farther apart and those toward the 50 inner side moving closer together. This movement of the two parts of the bogie throws the two axles more or less out of parallel according to the radius of the curve and causes each to take up a position radial 55 to the curve, and the flanges of the wheels to take up positions tangential to the rails so that they move around them freely without destructive wear.

I have shown and described a practical 60 application of my invention, but since there are numerous types of bogie vehicles to which it is applicable it will be evident that to apply it to such vehicles many modifications will be required which however will 65 present no difficulty to a competent work-

man. In particular for a locomotive consideration of the size and position of the cylinders, the width of gage and frame, and the height of the frame will render substantial modifications necessary.

70

What I claim as my invention is—

1. A bogie for a railway or tramway vehicle made in two parts, each part carrying one of the axles and the two parts being held together by a vertical king pin passing 75 through an eye in each of the two parts, such king pin being on one end of a link which has on its other end a second vertical pin that engages a beam rigidly secured to the frame of the vehicle body and holds there- 80 to a somewhat V-shaped beam upon the ends of which are two governor pins that engage and operate slidable governor blocks positioned and slidable between the opposed inclined faces of horn plates secured 85 to the two parts of the bogie.

2. In a bogie for a railway or tramway vehicle made in two parts each part having at one end an axle with a pair of wheels and at the other end an eye which takes the 90 king pin whereby the two parts are held together; two slidable blocks one on each side of the king pin positioned between oppositely inclined faces or horn plates with connections to the vehicle body so that as the 95 vehicle passes on to a curve the blocks are moved to one side or the other and alter the distance between the oppositely inclined faces or horn plates and so cause the two parts of the bogie to swing somewhat about 100 the king pin throwing the two axles more or less out of parallel according to the radius of the curve and causing them to take positions radial to the curve.

3. In a bogie for a railway or tramway 105 vehicle made in two parts each part having at one end an axle with a pair of wheels and at the other end an eye and having upon each side of the eye an inclined horn plate; a link having at its one end a downwardly 110 projecting pin passing through the said eyes and holding the two parts together and having at its other end an upwardly projecting pin engaging a beam secured to the frame of the vehicle body; and a somewhat V-shaped beam mounted at its center upon the said upwardly projecting pin and having at each end a downwardly projecting pin engaging and operating slidable 115 blocks slidable upon said inclined horn 120 plates.

4. In a bogie for a railway or tramway vehicle made in two parts each part having at one end an axle with a pair of wheels and at the other end an eye and having upon each side of the eye an inclined horn plate; a link having at its one end a downwardly 125 projecting pin passing through the said eyes and holding the two parts of the bogie together and having at its other end an up- 130

wardly projecting pin engaging a beam secured to the frame of the vehicle body; a somewhat V-shaped beam mounted at its center upon the said upwardly projecting pin 5 and having at each end a pin engaging and operating slideable blocks slideable upon said inclined horn plates; flanged bed plates secured upon the tops of the two parts of the bogie; and bearer blocks secured upon the 10 underside of the frame of the vehicle body resting and slideable upon the said flanged bed plates.

5. In a bogie for a railway or tramway vehicle made in two parts each part having 15 at one end an axle with a pair of wheels and at the other end an eye and having upon each side of the eye an inclined horn plate; a link having at its one end a downwardly projecting pin passing through the said eyes and holding the two parts of the bogie together and having at its other end an upwardly projecting pin engaging a beam secured to the frame of the vehicle body; 20 a somewhat V-shaped beam mounted at its center upon the said upwardly projecting pin and having at each end a pin engaging and operating slideable blocks made in two parts and slideable upon said inclined horn plates; springs carried by and projecting from brackets secured to the frame of the vehicle body adapted to engage the said slideable blocks when in normal position or when pushed outward but not when pushed inward; and bearer blocks secured upon the underside of the frame of the vehicle body resting and slideable upon flanged bed plates secured upon the tops of the two parts 25 of the bogie.

6. In a bogie for a railway or tramway vehicle made in two parts each part having 30 at one end an axle with a pair of wheels and at the other end an eye and having upon each side of the eye an inclined horn plate; a link having at its one end a downwardly projecting pin passing through the said eyes and holding the two parts of the bogie together and having at its other end an upwardly projecting pin engaging a beam secured to the frame of the vehicle body; 35 a somewhat V-shaped beam mounted at its center upon the said upwardly projecting pin and having at each end a pin engaging and operating slideable blocks slideable upon said inclined horn plates; springs carried by and projecting from brackets secured to the frame of the vehicle body adapted to engage the said slideable blocks when in normal position or when pushed outward but not when pushed inward; and bearer blocks secured upon the underside of the frame of the vehicle body resting and slideable upon flanged bed plates secured upon the tops of the two parts 40 of the bogie.

60

In testimony that I claim the foregoing as my invention I have signed my name in the presence of two subscribing witnesses this nineteenth day of September, 1918.

JOHN HENRY THOMAS.
